UNITED STATES PATENT OFFICE

149,620

DESIGN FOR A ROTARY TOOTHBRUSH

Harold W. Darr, Minneapolis, Minn., assignor to
The Kalla Co., Minneapolis, Minn., a corpora-
tion of Minnesota

Application November 2, 1946, Serial No. 134,477

Term of patent 14 years

(Cl. D9—2)

To all whom it may concern:

Be it known that I, Harold W. Darr, a citizen of the United States, residing at Minneapolis, in the county of Hennepin and State of Minnesota, have invented a new, original, and ornamental Design for a Rotary Toothbrush, of which the following is a specification, reference being had to the accompanying drawing, forming part thereof.

Referring to the drawing:

Fig. 1 is a top plan view of a rotary toothbrush, showing my novel design;

Fig. 2 is a side elevational view thereof;

Fig. 3 is a bottom plan view thereof;

Fig. 4 is a front elevational view thereof; and

Fig. 5 is a rear elevational view thereof.

I claim:

The ornamental design for a rotary toothbrush, as shown.

HAROLD W. DARR.
